WELL CORE DRILL

John H. Howard, Huntington Park, and Jesse C. Wright, Los Angeles, Calif., assignors to Globe Oil Tools Company, Los Nietos, Calif., a corporation of California

Application May 25, 1934, Serial No. 727,498

15 Claims. (Cl. 255—72)

This invention relates to a drilling tool and relates more particularly to a core drill for use in the rotary method of well drilling. A general object of this invention is to provide a simple practical and improved rotary core drill embodying an hydraulically actuated core catcher.

Another object of the invention is to provide a core drill embodying a practical and effective core catching and core retaining means that does not normally engage or in any way interfere with the core and that may be actuated from the upper end of the well to dependably grip and retain the core without operating or manipulating the drilling string.

Another object of the invention is to provide a core drill embodying a core catcher and a floating inner barrel or core receiving barrel that may be held against rotation through its engagement with the core and that is adapted to be moved longitudinally by fluid under pressure to actuate the core catcher.

Another object of the invention is to provide a core drill of the character mentioned including a novel and particularly effective swivel means for normally suspending the longitudinally shiftable inner barrel whereby it may be held against rotation with respect to the core due to its engagement therewith.

Another object of the invention is to provide a simple, practical core catcher that is rotatably supported in the bit head of the drill to float or be held against rotation during the drilling operation and that is actuated to grip the core by downward movement of the hydraulically actuated core barrel.

Another object of the invention is to provide a core drill of the character mentioned including a simple, dependable swivel means for suspending the inner barrel for rotation that is combined with a readily detachable valve on the upper end of the inner barrel.

A further object of the invention is to provide a core drill of the character mentioned that involves a single dependable latch for releasably holding the inner barrel in its up or unactuated position and that does not involve any pivoted levers, spring fingers or complicated valves that might be rendered inoperative during the drilling or coring operation.

Other objects and features of our invention will be better and more fully understood from the following detailed description of typical preferred forms and applications of the invention, throughout which description reference may be had to the accompanying drawings, in which:

Fig. 1 is a longitudinal detailed sectional view of the drill provided by this invention illustrating the inner barrel and the core catcher in their normal or unactuated positions. Fig. 2 is a view similar to Fig. 1 illustrating the inner barrel and the core catcher in the unactuated positions. Figs. 3 and 4 are enlarged transverse detailed sectional views taken as indicated by lines 3—3 and 4—4, respectively, on Fig. 1. Fig. 5 is an enlarged transverse detailed sectional view taken as indicated by line 5—5 on Fig. 2. Fig. 6 is an enlarged fragmentary elevation of the valve mounting and Fig. 7 is a fragmentary longitudinal sectional view of the lower portion of the drill illustrating a modified or alternative form of core catcher.

The core drill of the present invention includes, generally, an outer barrel 10 having a bit head 11 on its lower end, a core catcher 12 in the bit head 11, a longitudinally shiftable inner barrel 13 adapted to actuate the core catcher 12, means 14 for releasably suspending the inner barrel, and hydraulic means 15 for actuating the inner barrel 13 downwardly to operate the core catcher 12.

The outer barrel 10 of the drill is adapted to be attached to the operating or drilling string to be rotated therewith. The outer barrel 10 is an elongated tubular member provided at its upper end with a connecting member or sub 16. The sub 16 may have a tapered screw-threaded socket 17 in its upper end for receiving a threaded pin part on the drilling string for the purpose of attaching the barrel 10 to the string. A reduced longitudinal opening 18 is provided in the sub 16 and terminates at its lower end in a downwardly facing shoulder 19. A sub or connecting member 20 is provided on the lower end of the barrel 10 to carry the bit head 11.

The bit head 11 is operable to make an annular cut in the earth formation and thus provide a core for reception by the inner barrel 13. The bit head 11 includes a shoe or body 21 screw-threaded on the pin 20^a of the connecting member 20. Suitable cutting parts are provided on the bit head body 21. In the particular case illustrated in the drawings spaced stepped blades 22 project from the body 21 at circumferentially spaced points. The body 21 has a central longitudinal opening 23 to receive the core cut by the blades 22. An annular enlargement or recess 24 is provided in the upper end of the opening 23 to receive the end portion of the inner barrel 13.

The core catcher 12 is provided to grip and hold the core to break it free from the forma-

tion when the drill is raised and to retain the core in the barrel 13 when the drill is withdrawn from the well. The core catcher 12 is designed to be actuated by the inner barrel 13 when the inner barrel is moved downwardly by the hydraulic means 15. The core catcher 12 comprises a tubular member 25 arranged in the opening 23 of the bit head. The lower portion of the member 25 is recessed in the wall of the opening 23 at 26 and its upper portion projects through the recess 24. Rivets 27 removably attach the member 25 to the bit head body 21. A plurality of longitudinal slots extend downwardly through the projecting upper portion of the member 25 to divide it into a plurality of flexible fingers 28. Vertically spaced projections 29 are provided on the outer side of the fingers 28 and have bevelled upper and lower sides. The projections 29 are arranged in annular series and are adapted to be engaged by shoulders on the barrel 13 as will be subsequently described. It is to be particularly noted that the core catcher 12 just described presents a smooth interior surface that is inset from the wall of the opening 23 so that the core catcher does not engage or in any way interfere with the core as it passes into the drill.

The inner barrel 13 is provided to receive and hold the core and in accordance with the invention is shiftable longitudinally by the hydraulic means 15 to actuate the core catcher 12. The barrel 13 is arranged longitudinally in the outer barrel 10 and is suitably spaced from the interior of the outer barrel leaving an annular fluid passage P. In practice the inner barrel 13 may have comparatively thin walls as illustrated to be light in weight and to receive a core of maximum diameter. The inner barrel 13 extends downwardly into the bit head 11 and is provided at its lower end with an enlargement or collar 30. The collar 30 is movable longitudinally in the recess 24 and has a shoulder 31 adapted to bear upwardly against the lower end of the pin 20. The shoulder 31 and the end of the pin 20 may be hard faced or provided with wear taking bearing parts. The fingers 28 of the core catcher 12 project upwardly into the collar 30 and the interior of the collar is provided with spaced grooves 32 for normally receiving the projections 29 on the fingers. The upper walls of the recesses 32 form shoulders 33 which are adapted to engage the projections 29 to bend or flex the fingers 28 inwardly when the barrel 13 is moved downwardly to actuate the core catcher. An external enlargement or collar 34 is provided on the upper end of the inner barrel 13 to receive or cooperate with the swivel means 14 for suspending the inner barrel.

The means 14 rotatably suspends the inner barrel so that the inner barrel may be held against rotation relative to the core during the drilling or coring and the means 14 is releasable by the hydraulic means 15 to permit the inner barrel to move downwardly under fluid pressure to actuate the core catcher 12. The swivel means 14 includes a wash pipe 35 shiftable in the opening 18 of the sub 16. The wash pipe 35 is preferably keyed to the sub 16. In the drawings we have shown a key 36 on the wash pipe 35 operating in a key-way 37 in the wall of the opening 18. The opening 38 in the wash pipe is at all times in communication with the lower end of the drilling string. The upper end of the opening 38 is open to the interior of the drilling string and lateral ports 39 are provided in the wall of the wash

pipe to connect the opening 38 with the space P between the two barrels. A rotatable connection or swivel connection is provided between the wash pipe 35 and the upper end of the barrel 13. The swivel connection includes a lower member 40 and an upper member 41. The lower member 40 is arranged in the collar 34 and engages the lower end of the wash pipe 35. A flange 42 is provided on the lower end of the wash pipe 35. The upper member 41 is screw-threaded to the member 40 and surrounds the lower portion of the wash pipe 35. A downwardly facing shoulder 43 is provided on the upper member 41 to engage the flange 42. With the construction just described the connected members 40 and 41 are rotatable on the wash pipe 35 and are connected for movement therewith by the engagement of the member 40 with the lower end of the pipe and the engagement of the shoulder 43 with the flange 42.

The means 14 includes a releasable bayonet lock connection between the upper swivel member 41 and the inner barrel 13. A plurality of bayonet slots 44 extend into the collar 34 from its upper end. The slots 44 have lateral branches or recesses 45 at their lower ends. Ribs 46 are provided on the collar 34 to reinforce the collar at the bayonet slots. A plurality of lugs 46 are provided on the swivel member 41 to cooperate with the bayonet slots. The lugs 46 are adapted to be passed longitudinally through the slots 44 and turned into the recesses 45. A pivoted lock member 47 normally fills one of the longitudinal portions of a slot 44 to prevent the accidental displacement of the lugs 46 from the lateral recesses 45 of the slots. It will be seen that the swivel connection and the bayonet slot connection rotatably connect the inner barrel 13 with the wash pipe 35.

The invention includes a releasable latch 48 for normally connecting the wash pipe 35 with the sub 16 to suspend the inner barrel 13 in its up position where the projections 29 are received in the grooves 32. The latch 48 is releasable by the hydraulic actuating means 15 to allow the inner barrel 13 to be moved downwardly by fluid pressure. The latch 48 is in the form of a plunger or bolt shiftable in a lateral opening 49 in the sub 16. The outer portion of the opening 49 is enlarged and is closed by a plug 50. A spring 51 is arranged under compression between the plug 50 and the outer end of the latch 48 to yieldingly urge the latch inwardly to cooperate with the wash pipe 35. A flange 52 is provided on the latch 48 to limit the inward movement of the latch. The latch 48 normally projects through an opening 53 in the wash pipe 35 to suspend the wash pipe and the inner barrel 13. In accordance with the invention the latch 48 extends completely through the opening 53 and projects into the opening 38 of the wash pipe. The projecting inner end of the latch 48 is sharpened or beveled as illustrated in the drawings. The opening 49 is preferably packed with grease or the like.

During the drilling or coring operation circulation fluid is continuously pumped downwardly through the drilling string. This circulation fluid passes through the wash pipe 35 and flows downwardly through the passage P to the bit head 11. Ports 54 are provided in the collar 30 to convey the circulation fluid to an annular recess 55 on the interior of the bit head body 21. Spaced longitudinal ports 56 extend from the recess 55 to the lower end of the bit head to discharge downwardly into the well bore. It is desirable

to prevent the downwardly flowing circulation fluid from entering the inner barrel 13. A valve seat 57 is provided in the wash pipe 35 below the ports 39 and a ball valve 58 is provided to cooperate with the seat 57 to prevent the entrance of circulation fluid to the inner barrel. The ball valve 58 moves off of the seat 57 to permit fluid that may be trapped in the barrel 13 to discharge as the core is received in the barrel.

The hydraulic actuating means is operable to release the latch 48 from the wash pipe 35 and then force the inner barrel 13 downwardly to actuate the fingers 28 of the core catcher inwardly to grip the core. The hydraulic actuating means 15 includes a valve seat 60 on the interior of the wash pipe 35 between the ports 39 and the latch receiving opening 53. The seat 16 may be in the nature of an internal enlargement on the wash pipe. The means 15 also includes a valve member or plunger 61 adapted to be dropped or pumped downwardly through the drilling string to first engage and release the latch 48 and then cooperate with the seat 60 to close the opening 38 of the wash pipe. The plunger 61 is sufficiently long to close the latch receiving opening 53 in the wall of the wash pipe when in contact with the seat 60.

When a core of sufficient length has been received the valve member or plunger 61 may be dropped or pumped downwardly through the drilling string to enter the wash pipe 35 and come to rest on its valve seat 60. During its movement through the wash pipe 35 the tapered or pointed end of the plunger engages the projecting end of the latch 48 to move the latch inwardly against the action of the spring 51. When the latch is moved inwardly in this manner the wall of the opening 53 engages the tapered end of the latch and downward force on the wash pipe causes the latch to be further moved outwardly out of engagement with the wash pipe. When the plunger 61 is seated on the seat 60 the pump pressure on the circulation fluid in the drilling string acts downwardly against the upper end of the wash pipe 35 and the plunger 61 to force the inner barrel 13 downwardly. An area equal in diameter to the external diameter of the wash pipe 35 is acted upon by the circulation fluid.

The invention includes means for informing the driller of the full actuation of the inner barrel 13 and the core catcher 12 and for resuming the circulation of fluid through the tool. A lateral port 70 is provided in the wall of the wash pipe 35 in a plane above the plane of the opening 53. Upon the inner barrel 13 reaching its lowermost position where the end of the collar 30 is at the bottom of the recess 24 the port 70 passes or partially passes the shoulder 19 to put the opening 38 of the wash pipe and the interior of the drilling string in communication with the passage P. This automatically relieves the pressure on the fluid in the string so that the pump no longer labors indicating to the driller that the tool has been fully actuated.

Fig. 7 of the drawings illustrates a form of core catcher 12^a that is free to float or rotate in the bit head. The core catcher 12^a comprises a tubular member 25^a which is similar generally to the member 25 described above. The member 25^a is inset in the opening 23 of the bit head and has spaced upwardly extending fingers 28^a adapted to be bent inwardly against the core. The fingers 28^a have projections 29^a engageable by shoulders 33^a on the inner barrel to cause inward

bending of the arms upon downward movement of the inner barrel. In accordance with this form of the invention an annular outwardly projecting flange 80 is provided on the lower end of the member 25^a. A ring 81 is arranged in the recess 24^a of the bit head immediately above the flange 80 to limit upward movement of the core catcher in the bit head. The flange 80 rotatably seats on the shoulder 26^a in the bit head opening. The core catcher member 25^a is supported in the bit head for free rotation. The operation of the core catcher 12^a and the other parts is the same as in the form of the invention illustrated in Figs. 1 to 5, inclusive, of the drawings.

The drill is run into the well on the lower end of the operating string with the latch 48 engaging in the opening 53 to suspend the inner barrel 13 in the position where the core catcher 12 is unactuated. When the drill has reached the bottom of the well circulation fluid may be passed downwardly through the string to flush the tool of sand or solid matter. The ball valve 58 may be dropped through the string, after the flushing of the tool, to come to rest on the seat 57. The circulation of the fluid may be resumed and the drilling or coring operation started. The bit head 11 makes an annular cut in the earth formation leaving a core which is received by the inner barrel 13. The drill is rotated in accordance with the usual practice in the rotary method of well drilling and the inner barrel 13 which is swivelly supported from its upper end may be held against rotation through its engagement with the core. This prevents the breaking or wearing away of the core through engagement with the inner barrel. The downward thrusts are transmitted from the outer barrel 10 to the inner barrel through engagement of the pin 20^a with the shoulder 21 so that the latch 28 and the swivel 40 connection are relieved of these strains. The core catcher 12, which is inset in the wall of the bit head opening 23 allows the core to pass into the inner barrel 13 with substantial clearance and does not engage the core.

When a core of sufficient length has been obtained the plunger 61 is dropped or pumped through the drilling string to enter the wash pipe 35. In passing through the wash pipe the plunger 61 moves the latch 48 outwardly out of the opening 53. The plunger 61 seats or comes to rest on the seat 60 to cut off the downward flow through the drilling string. The pressure on the fluid in the string then acts on the upper end of the wash pipe 35 and the plunger 61 to positively force the inner barrel 13 downwardly. The weight of the inner barrel 13 and the connected parts of course tends to move the inner barrel downwardly. Upon downward movement of the inner barrel the shoulders 33 cooperate with the projections 29 on the fingers 28 to flex or bend the fingers inwardly into the core. The fingers 28 are capable of substantial inward movement and obtain a firm dependable grip on the core. As the inner barrel 13 reaches its fully actuated position the port 70 comes into communication with the passage P relieving the pressure on the circulation fluid to inform the driller of the full actuation of the tool. When the port 70 communicates with the passage P the circulation of fluid through the tool is automatically resumed. Upon the drill being raised the fingers 28 which are biting into the core cause the core to be broken away from the formation and the fingers support the core in the inner barrel 13 when the drill is pulled from

the well. After the drill has been pulled to the surface the outer barrel 10 may be disconnected from the bit head 11 and pulled upwardly from around the inner barrel 13. The 5 bayonet slot connection between the swivel member 41 and the inner barrel 13 is such that the wash pipe 35 and the parts of the swivel connection may be easily disconnected from the inner barrel.

10. The core drill of the present invention embodies a core catcher that is positively actuated by fluid under pressure acting to move the inner barrel downwardly. The invention provides a simple dependable means for swivelly suspending the inner barrel from its upper end and for releasing the inner barrel for downward movement by the hydraulic means.

Having described only typical preferred forms and applications of our invention we do not wish 20 to be limited or restricted to the specific forms and applications herein set forth, but wish to reserve to ourselves any modifications or variations that may appear to those skilled in the art or fall within the scope of the following claims:

25. Having described our invention, we claim:

1. In a core drill having an outer barrel and a bit head on the lower end of the outer barrel, a longitudinally movable inner barrel within the outer barrel, means rotatably supporting the inner barrel on the outer barrel comprising a member rotatably connected with the inner barrel, and a latch connecting the member to the outer barrel, means for moving the inner barrel downwardly, and a core catcher in the bit head actuated by downward movement of the inner barrel.

30. 2. In a core drill, an outer barrel, an inner barrel movable longitudinally in the outer barrel, means normally rotatable suspending the inner barrel including a releasable spring held latch, a core catcher actuated by downward movement of the inner barrel, and means for releasing the latch and moving the inner barrel downwardly.

35. 3. A drill including, an outer barrel having a bit head on its lower end, an inner barrel arranged for longitudinal movement in the outer barrel, core catching means actuated by longitudinal movement of the inner barrel, releasable means normally rotatably supporting the inner barrel against longitudinal movement including a spring held latch, and means for releasing the latch and moving the inner barrel longitudinally to operate the core catching means including an object to be dropped through the drilling string to cooperate with the latch and then transmit 50 pressure to the inner barrel.

40. 4. A drill including, an outer barrel having a bit head on its lower end, an inner barrel arranged for longitudinal movement in the outer barrel, core catching means actuated by downward movement of the inner barrel, a member keyed to the outer barrel for longitudinal movement therein and rotatably connected to the inner barrel, a releasable latch normally holding the member against downward movement, and means for releasing the latch and moving the inner barrel downwardly.

45. 5. A well drill including, an outer barrel having cutting means on its lower end, an inner barrel having its lower end rotatable and longitudinally movable in the outer barrel, means rotatably supporting the upper end of the inner barrel and releasably holding the inner barrel against downward movement, a core catcher actuated by downward movement of the inner barrel.

rel, and means releasing said means and moving the inner barrel downwardly.

6. A well drill for use on a tubular drilling string including, an outer barrel to be attached to the lower end of the string, an inner barrel shiftably and rotatably arranged in the outer barrel to receive a core, core catching means adapted to be actuated by downward movement of the inner barrel, releasable means holding the inner barrel against downward movement, and means actuated by fluid passed through the string to release said means and move the inner barrel downwardly.

7. A well drill for use on a tubular drilling string including, an outer barrel to be attached to the lower end of the string, an inner barrel shiftably and rotatably arranged in the outer barrel to receive a core, core catching means adapted to be actuated by downward movement of the inner barrel, releasable means holding the inner barrel against downward movement, and means actuated by fluid passed through the string to release said means and move the inner barrel downwardly, the last mentioned means including a member to be passed through the string.

8. A well drill for use on a tubular drilling string including, an outer barrel to be attached to the lower end of the string, an inner barrel shiftably and rotatably arranged in the outer barrel to receive a core, core catching means adapted to be actuated by downward movement of the inner barrel, a longitudinally shiftable member in the outer barrel, releasable means holding the member against movement, a swivel connection between the member and the upper end of the inner barrel, and an object to be dropped through the string to release the releasable means.

9. A well drill for use on a tubular drilling string including, an outer barrel to be attached to the lower end of the string, an inner barrel shiftably and rotatably arranged in the outer barrel to receive a core, core catching means adapted to be actuated by downward movement of the inner barrel, a tubular member shiftable in the outer barrel and normally passing fluid pumped through the string, a swivel connection between the member and the inner barrel, releasable means normally holding the member against movement, and an object to be passed through the string to release said means and close the member whereby fluid pressure forces the inner barrel downwardly.

10. A well drill for use on a tubular drilling string including, an outer barrel to be attached to the lower end of the string, an inner barrel shiftably and rotatably arranged in the outer barrel to receive a core, core catching means adapted to be actuated by downward movement of the inner barrel, a tubular member shiftable in the outer barrel and normally passing fluid pumped through the string, a swivel connection between the member and the inner barrel, releasable means normally holding the member against movement, and an object to be passed through the string to release said means and close the member whereby fluid pressure forces the inner barrel downwardly, the member having a port opened upon actuation of the core catcher to resume circulation through the drill.

11. In a well drill, an outer barrel having a bit head on its lower end, a core catcher in the bit head comprising a plurality of fingers, an inner barrel for receiving a core, means for moving the inner barrel downwardly, projections on

the fingers, and parts on the inner barrel cooperating with the projections upon downward movement of the inner barrel to flex the fingers inwardly.

5 12. A core drill including, an outer barrel, an inner core receiving barrel, and means for rotatably supporting the inner barrel including a tubular member carried by the outer barrel and having communication with its interior, a tubular assembly swivelly connected to the tubular member, and a releasable connection between the assembly and the inner barrel.

10 13. In a core drill, an outer barrel, an inner core receiving barrel, a tubular member connected to the outer barrel, an assembly swivelly connected to the member, a releasable bayonet connection between the assembly and the inner barrel, and a valve in the member preventing the entrance of fluid to the inner barrel.

15 14. In a core drill having an outer barrel and a bit head on the lower end of the outer barrel, a longitudinally shiftable inner barrel within the outer barrel, means normally rotatably supporting the inner barrel, means for moving the inner barrel downwardly, a core catcher rotatably

supported in the bit head and actuated by downward movement of the inner barrel spaced opposing shoulders on the interior of the bit head, and a part on the core catcher operating between the shoulders to prevent longitudinal movement 5 of the core catcher.

15 16. A well drill including, an outer barrel having cutting means on its lower end, an inner barrel having its lower end rotatable and longitudinally movable in the outer barrel, a tubular 10 member slidable in the outer barrel, a disengageable swivel connection between the member and the upper end of the inner barrel, a releasable latch holding the member against movement and projecting into the interior of the member, a seat in the member, an object to be dropped through the drilling string to enter the member, release the latch and then come to rest on the seat to close the member whereby pressure on 20 the string forces the inner barrel downwardly, and a core catcher actuated by downward movement of the inner barrel.

JOHN H. HOWARD.

JESSE C. WRIGHT.
